UNITED STATES PATENT OFFICE.

CHARLES A. MORTON, OF NEW YORK, N. Y., ASSIGNOR TO WESTERN ELECTRIC COMPANY, INCORPORATED, OF NEW YORK, N. Y., A CORPORATION OF NEW YORK.

AUTOMATIC TELEPHONE SYSTEM.

Application filed December 1, 1924. Serial No. 753,027.

This invention relates to automatic telephone systems, more especially to such systems using call charging apparatus, and is particularly adapted for use in conjunction with a metering circuit arrangement for systems of this character.

The object of the invention is to provide an improved circuit arrangement for automatically operating the charging device associated with the calling line upon the completion of a connection to an ordinary line and for preventing the operation of the charging device associated with the calling line when a connection is established with a free line, so called, that is on calls to officials of the telephone company, police or fire departments, etc.

In accordance with this invention, means is provided for reversing the direction of the flow of current in the calling line when the connector is set upon an ordinary line or upon one of a group of ordinary lines, said current reversing means being rendered inoperative, however, whenever a connector is set upon a free line or upon one of a group of free lines, it being understood that whenever the direction of the flow of current applied to the calling station is reversed, the call charging mechanism associated with the calling line is operated to charge for the call.

Referring to the drawing, comprising but a single sheet, Fig. 1 shows a calling subscriber's line, a primary line switch, a selector, a connector, and a called subscriber's line; and Figs. 2 and 3 show modified forms of the invention.

Only so much of the circuits are shown as is necessary to comprehend the invention. It should be understood, however, that this invention may be used in a system such, for example, as the one shown in the patent to Wicks No. 1,379,068, issued May 24, 1921 and Reissue No. 15,762 of Feb. 12, 1924.

It is thought that the invention will be more clearly understood from the detailed description of the operation of the system. When the subscriber at the calling station 1 removes the receiver to initiate a call, circuits are closed to operate the line switch or switches as described in said Wicks patent to extend the calling line to the selector S so that the spring contacts 10, 11 and 12 will engage the spring contacts 20, 21, and 22. The impulse relay, not shown but which is

included in the square designated 5, operates 55 in series with the loop of the calling station 1 and connects ground in a manner not shown, but which is disclosed and described in said Wicks patent, to the lead 44. Relay 3 is held by way of conductor 44 to this 60 ground and relay 8 operates in parallel with relay 3 to the same ground and functions in a manner hereinafter described. The message register 4 which is in parallel with relay 3 does not operate at this time. The dial 65 (not shown) at the calling station 1 is now operated causing the selector setting mechanism (not shown but included in the square designated 5) to operate in the well-known manner and set the brushes 30, 31, and 32 of 70 the selector S upon the terminals of an idle trunk leading to one of the switches of the next switch group. While it should be understood that several such switches may be inserted between the selector S and the connector C without departing from the spirit 75 of this invention, we will assume that the brushes 30, 31, and 32 are now resting upon the terminals 40, 41, and 42 associated with the connector C. Under these conditions, a 80 circuit including the impulse relay 13, polarized relay 6, and the loop at the calling station 1 will be closed and relay 13 will operate closing an obvious circuit to operate relay 15. Relay 6, which is polarized, will 85 not operate at this time due to the direction of the flow of current in its winding.

When the dial at the calling station 1 is operated and released in accordance with the tens digit of the called number, the circuit 90 including the impulse relay 13 is interrupted at the calling station 1 and relay 13 follows these interruptions or impulses. When relay 13 releases, a circuit is closed to operate the primary magnet 17 and relay 16 in series 95 by way of contact 37, right-hand armature and front contact of relay 15, armature and back contact of relay 13 to ground. The primary magnet 17 and relay 16 operate over this circuit, the former causing the 100 brushes 34, 50, 51, and 52 secured to the brush shaft (not shown) to be stepped one step in the primary movement of the connector C. During this first step, the contact 37 of the off-normal contact springs ON is opened 105 and the contact 38 is closed. During each subsequent impulse of the impulse train, relay 13 releases and the primary magnet 17

again operates continuing the primary movement of the switch shaft. The stepping circuit may now be traced from battery, winding of magnet 17, through the winding 5 and front contact of relay 16, contact 38, right contacts of relays 15 and 13 to ground. Relays 15 and 16 which are slow to release remain operated during the impulse period. At the end of the impulse train, relay 16 releases preparing a circuit for the secondary magnet 18 which operates as hereinafter described. The brush 34 is now resting upon one of the terminals 35, 36, etc. of the commutator X.

15 The dial is again operated and released in accordance with the units digit of the called line, which we will assume to be the station 2, in which case the digit 1 is dialed. The secondary magnet 18 is now operated 20 under control of impulse relay 13 and slow relays 15 and 16, relay 15 being operated and relay 16 released. The circuit for the secondary magnet may be traced from battery through the winding of said magnet, 25 back contact of relay 16, contact 38, to ground through the right contacts of relays 15 and 13. The secondary magnet 18 operates the switch shaft carrying the brushes 34, 50, 51, and 52 in the secondary movement of the switch and brushes 50, 51, and 52 will come to rest upon the terminals 60, 61, and 62, respectively, of the called line 2. The connector switch C will test the busy or 30 idle condition of the called line in a manner, not shown, but which is disclosed and described in the patent to Wicks cited. We will assume the called station 2 is idle, in which case, ground will be connected by way of brush 52 and terminal 62 to operate relay 40 35 through its right winding.

Ringing current is now connected to the called line in a manner, not shown, but which is disclosed and described in said Wicks patent. We will assume the called station 2 to be an ordinary line, that is, a line for calls to which the calling station is to be charged. In this event, the brush 34 will be resting upon the terminal 36 or some other similar terminal which is connected to ground. It 50 will be remembered that the brush 34 came to rest upon one of these terminals at the end of the primary movement of the connector C and it should be understood that the brush 34 is so arranged that it remains in contact with the terminal 36 or some similar terminal during the secondary movement of the switch and until the connector C is restored to normal. It should be further understood that all the lines upon the level 55 selected will be ordinary lines, the same as the called line 2, the lines to which the connector C has access being segregated in groups depending upon whether they are ordinary lines or free lines.

60 When the receiver is removed at the called

station 2, in response to the ringing signal, a circuit is closed including the windings of relay 24 and the loop of the called station 2 operating relay 24. With the brush 34 resting upon grounded terminal, for example 70 36, an obvious circuit is closed to operate relay 14. The relay 14 operated reverses the direction of the flow of current supplied through the windings of relay 13 to the calling station 1. Relay 6, which is included 75 in this circuit, is polarized and responds to said current reversal. The operation of relay 6 closes a circuit by way of its armature and front contact, brush 32, to ground under control of relay 15, to operate relay 7. 80 Relay 7 operated locks by way of brush 32 under control of relay 15. The operation of relay 7 opens at its right-hand armature and back contact the circuit previously established to operate slow-to-release relay 8, and 85 connects the booster battery 9 by way of terminal 22 and brush 12 to the winding of the meter 4 which operates to charge the call. Relay 3 remains operated under this circuit condition. When slow-to-release relay 8 releases, the booster battery 9 is disconnected from the meter 4 and the relay 3, but the meter and relay remain operated in parallel by way of 12, 22, left-hand inner armature and front contact of relay 7, normal contacts of relay 8, 44, 32, 42, armature and front contact of relay 15 to ground.

Assume, however, that the connector C instead of being set upon the terminals 60, 61, and 62 associated with the called line 2, 100 had been set upon the terminals associated with a free line then the brush 34 would have been resting upon the terminal 35 or some similar non-grounded terminal. In this event, when the called station answered 105 the circuit to operate relay 14 would not have been closed; hence, the direction of the flow of current supplied through the windings of relay 13 to the called line, would have remained unchanged and the polarized relay 6 would have remained inoperative, hence the circuit to operate the meter 4 would not have been closed.

In any event, when the receiver is replaced upon the switchhook at the calling station 1, the impulse relay 13 releases, opening the circuit through the winding of slow-to-release magnet 15, which likewise releases, and the release magnet 19 is operated over a circuit (not shown) to restore the 110 connector C to normal.

In Fig. 2, an alternative arrangement is shown, whereby it becomes unnecessary to maintain the brush 33 in contact with the terminals 26, 27, etc., of the commutator, 125 during the secondary movement of the connector C. An additional relay 25 is provided which operates as soon as relay 16 releases at the end of the primary movement providing the brush 33 is resting upon a 130

grounded terminal. In case relay 25 operates, it closes a locking circuit by way of its right-hand armature and front contact, contact 23, and the armature of the release magnet 19, to ground. During the secondary movement of the connector, brush 33 may break contact with the terminal of the commutator without affecting the operation of the connector in any way. When the receiver is removed from the switchhook at the called station, relay 24 operates as before. Relay 14, however, will not operate unless relay 25 is locked up, since the closing of the operating circuit for relay 14 depends upon the operated condition of relay 25. Relay 14 functions in the manner previously described in connection with the description of Fig. 1.

Fig. 3 shows another modification of Fig. 1 which may be used when it is desirable to mingle ordinary lines and free lines indiscriminately at the connector bank instead of segregating the free lines from the ordinary lines, as shown in Figs. 1 and 2. Whenever it is desired to mix the free and the ordinary lines indiscriminately, it is necessary to furnish an extra brush and an additional row of contacts in the terminal bank, as indicated in Fig. 3. The commutator X and brush 34, however, are not required. The extra terminal associated with the ordinary lines is connected to ground, as indicated at 73, while the extra terminal associated with the free lines remains ungrounded, as indicated at 63. When the called station answers and relay 24 operates in the manner previously described, relay 14 will operate providing the brush 53 is resting upon a grounded terminal such, for example, as terminal 73, but will not operate whenever the brush 53 is resting upon a non-grounded terminal such, for example, as terminal 63. Relay 14 functions to control the reversing of the flow of current in the calling line in the manner previously described in connection with the description of Fig. 1.

While for purposes of illustration, the invention has been shown in conjunction with a calling line equipped with a meter, it is not so limited, but may be used to control the coin box mechanism at a calling station. Lines of this type are disclosed in the patent to Stokely, No. 1,452,323 issued April 17, 1923.

What is claimed is:

1. In a telephone system, a calling line, called lines, an automatic switch for interconnecting the same, means in said automatic switch for supplying talking battery to said calling line, a relay for reversing the direction of the flow of current in the calling line, a local circuit for said relay, means dependent upon the classification of the called line for either extending or preventing the extension of said local circuit, and means re-

sponsive to the called line in answering for closing said local circuit to operate said relay.

2. In a telephone system, a calling line, called lines an automatic switch for interconnecting the same, means for producing a flow of current in said calling line, a relay operable to reverse the direction of said current flow, a local circuit for said relay, a supervisory relay, means dependent upon the classification of the called line for extending said local circuit to said supervisory relay, and means responsive to the called line in answering for operating said supervisory relay to close said local circuit. 70 75 80

3. In a telephone system, a calling line, called lines classifiable as free or as charge lines, an automatic switch for establishing a talking circuit between said lines, means in said automatic switch for producing a flow 85 of current in said calling line, a relay operable to reverse the direction of said current flow, means responsive to the setting of the switch on a charge line for preparing for said relay a circuit independent of said talking circuit and means responsive to the called line in answering for completing said relay circuit. 90

4. In a telephone system, a calling line, called lines classifiable as free or as charge 95 lines, an automatic switch for establishing a talking connection between said lines, means in said automatic switch for producing a flow of current in said calling line, means for reversing the direction of said current 100 flow, means responsive to the setting of the switch on a charge line for preparing an operating circuit for said current reversing means independent of said talking connection, and means in the switch responsive to the called line in answering for completing the circuit of said current reversing means. 105

5. In a telephone system, a calling line, an automatic switch, called lines appearing in said switch as free lines and charge lines, means for operating said switch to establish a talking connection between the calling line and a called line, a group of contacts having different electrical conditions thereon for discriminating between a free and a charge 110 115 120 line, means for producing a current flow in the calling line, a relay for reversing the direction of said current flow, a circuit for said relay, separate from said talking connection, a brush coating with said contacts to close said circuit when the switch selects a charge line and to maintain the circuit open when the switch selects a free line, and a message register responsive to a reversal of current. 125

In witness whereof, I hereunto subscribe my name this 21st day of November A. D., 1924.

CHARLES A. MORTON.
